UNITED STATES PATENT OFFICE.

NED EARL HAYWARD, OF HOLYOKE, MASSACHUSETTS.

FREIGHT-CAR SIGNAL.

Application filed March 26, 1923. Serial No. 627,647.

To all whom it may concern:

Be it known that NED E. HAYWARD, a citizen of the United States, residing at Holyoke, in the county of Hampden and 5 State of Massachusetts, has invented certain new and useful Improvements in Freight-Car Signals, of which the following is a specification.

In carrying out the present invention, it 10 is my purpose to provide a signal adapted for attachment to freight cars whereby the device may be moved to such a position for indicating the fact that the car has been loaded or unloaded and that the same may be 15 moved from the yard.

A further purpose of my invention resides in the provision of such a signal that may be readily applied to all types of freight cars, the device being comparatively simple of 20 construction and relatively inexpensive in application to cars, the same comprising but few parts and these so correlated as to reduce the liability of derangement to a minimum.

25 The nature and advantages of the invention will be better understood when the following detailed description is read in connection with the accompanying drawings, the invention residing in the construction, 30 combination, and arrangement of parts as claimed.

In the drawings forming part of this application, like numerals of reference indicate similar parts in the several views, and 35 wherein:

Figure 1 is an end elevational view of a freight car equipped with my improved signal, the same being shown in both raised and lowered positions;

40 Figure 2 is a fragmentary side elevation of the car, the signal being shown in side elevation and in a raised indicating position;

Figure 3 is a transverse cross section upon 45 the line 3-3 of Figure 1; and

Figure 4 is a perspective of the signal plate per se.

Referring to the drawings in detail, 5 designates a freight car of conventional design. My invention embodies the provision of a pair of T arms 6 bolted or otherwise secured at spaced points upon one end of the car, the ends of these arms being formed with bearing collars 7.

55 Freely movable within the bearing collars of said arms 6 is a relatively elongated rod

8 upon the upper end of which is detachably secured an indicating plate 9. The lower longitudinal edge of this plate, as more clearly shown in Figure 4, is formed with 60 a sleeve 10 which engages over the said rod 8 and is secured thereto by a set screw or the like 11.

Adjacent the end of the rod carrying said plate 9 is a collar 12, the same being adjustably secured to the rod through the medium of a set screw 13, it of course being understood that this collar engages with the bearing collar 7 of the uppermost T arm when the rod is dropped to an unindicating position for limiting the downward movement of the rod within the bearing collars.

65 Adjacent the lower end of the rod there is provided a cross slot, the same adapted for reception of a pin 14, the ends of which 70 have contact with the lowermost bearing collar for retaining the rod in its raised indicating position, as per the full lines of Figure 1. It is preferable that this pin 14 be secured to the T arm through a chain section 15.

75 In view of the above description it will at once be apparent that I have provided a signal for freight cars wherein when the car has been loaded or unloaded and it is desired 80 that the same be moved from the yard the rod 8 may be extended to a raised position and maintained in such a position by the pin 14 and even though I have herein shown and described the most practical embodiment of the invention with which I am now 85 familiar it is nevertheless to be understood that minor changes may be made therein, without departing from the spirit and scope 90 of the invention as claimed.

95 Having thus described my invention, what I claim as new and desire to secure by Letters Patent is:

1. In combination with a freight car, an 100 indicating member slidable within bearings upon one end of the car, means for maintaining the indicating member in a raised position whereby the same may be viewed, and means for limiting the downward movement 105 of the indicating member within said bearings.

2. In combination with a freight car, a 110 pair of spaced bearing members in vertical alignment upon one end of the car, a rod slidable within said bearing members, an indicating plate upon the upper end of said rod, means for securing the rod in a raised

position whereby the indicating plate may be viewed, and means for limiting the downward movement of the rod within said bearing members.

5. 3. In combination with a freight car, a pair of spaced bearing collars upon one end of the car and adjacent one side thereof, a rod freely slideable within said collars, an indicating plate upon the upper end of the rod, an adjustable collar upon said rod between the uppermost bearing collar and said indicating plate, said adjustable collar

adapted for support upon the uppermost bearing collar for limiting the downward movement of the rod within the bearing collars, said rod being formed with an opening at a point adjacent its lower end, and a cross pin adapted for reception within said opening, and for support upon the lowermost bearing collar for maintaining the rod 15 in a raised position, whereby the indicating plate may be viewed. 20

In testimony whereof I affix my signature.
NED EARL HAYWARD.
